TOOL FOR CLOSING PARACHUTE PACKS

Filed May 6, 1944

FIG. 1

UNITED STATES PATENT OFFICE

2,357,805

TOOL FOR CLOSING PARACHUTE PACKS

Ralph T. Bixon, Chicago, Ill.

Application May 6, 1944, Serial No. 534,515

3 Claims. (Cl. 254—67)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to tools or implements for closing parachute packs, and the general object of the invention is to provide a device which will facilitate drawing the straps of a parachute pack together, so that the rip cord needles may be inserted to secure the pack in properly assembled condition. The device of the invention may be advantageously used by persons of little strength or skill to perform the final steps in assembling parachute packs. The preferred device is of simple construction, is readily manufactured, is inexpensive and durable.

I am aware that it is not new to employ a screw device to draw the ends of a strap together, for example around a trunk, and in this connection reference is made to the Smith Patent No. 96,843, dated November 16, 1869. In the Fremeau Patent No. 2,335,589, dated November 30, 1943, a parachute tool is disclosed employing a lever and ratchet for drawing the loops on the parachute straps over the prongs of the pack, so that the pack may be secured.

In the accompanying drawing,

Fig. 1 is a plan view, more or less diagrammatic, of a parachute pack showing the device of the invention in the act of drawing the eye members together;

Fig. 2 is a perspective view, on an enlarged scale, of the device, shown from the underside;

Fig. 3 is a detail in elevation on a still larger scale;

Fig. 4 is another detail in side elevation;

Fig. 5 is a sectional elevation on a large scale showing the fastening means for the parachute pack; and

Fig. 6 is a detail in plan of the eye member, shown attached to a strap.

Referring particularly to the drawing, a parachute (not shown) is assumed to be folded within a cover 5 which is usually of stitched canvas, with a fold 6 overlying fold 7, and end folds 8, 9 each overlying folds 6 and 7. The illustrated parachute pack cover is of simplified construction, and various details which are unnecessary in the present disclosure are omitted. The six elastic cords 10 which automatically open the parachute pack are however shown, with their hooks 11 disengaged from the eyes 12. These cords are under considerable tension when the hooks and eyes are engaged. Cloth straps 13, 14 are stitched as at 15 to the end folds or flaps

8, 9, and have eye members 16 at their ends, each eye member having a circular eye 16a and shoulders 16b projecting laterally on either side of strap 13 (or 14). The eyes 16a are of such size that they will fit over metal prongs or cones 17 secured to fold 7 of the parachute cover and projecting through eyelets 18, which are secured to fold 6. The construction is illustrated in Fig. 5, which also shows one of the rip cord needles 19 passed through an aperture 20 extending laterally through one of the prongs or cones. So long as the rip cord needle lies in the aperture 20, the eye member 16 is locked, and the tensioned strap 13 or 14 attached thereto is ineffective; but when the rip cord needle is pulled out, there is nothing to hold the eye member 16 on the prong or cone, and it flies off, under the tension to which it is subjected by the strap and the folded parachute, and the pack then opens on all sides to release the parachute.

Primarily because of the resiliency of the many folds of the parachute, the final drawing into position of the eye members 16 requires considerable strength, often more than women operators are able to exert, especially if the task is to be repeated many times during a work-shift. To facilitate this operation, the device of the invention is employed as will now be described.

The preferred device is adapted to engage eye members 12 and comprises an elongated flat plate 21, preferably of metal, with forked end members 22 at one end each having a hook 22a. These hooks 22a are so spaced apart and are of such shape that they may engage the shoulders 16b of one of the eye members 16 on each side of strap 13 or 14, Fig. 1. Plate 21 has a central slot 23 for receiving prongs 17 and permitting access to said prongs to insert the rip cord needles while the closing device is still applied to the parachute pack. At the opposite end of plate 21 a lug 24 is secured, and this lug receives one end of a lead screw 25, the screw being held against rotation by a cross pin or rivet 26 passing through the lug and screw. A clamp member 27 is freely slidable on the lead screw and has arm 27a slidable on plate 21 and lying parallel to the axis of the lead screw. A pair of spaced hooks 27b are struck out from arm 27a and are adapted to engage eye member 16 on either side of its belt 14, as indicated. A nut 28 having a knurled periphery 28a is threaded on the lead screw 25 and has a boss 28b engaging a boss 21c projecting from the opposed face of the clamp member 27. Nut 28 is sufficiently large to be easily turned by hand, and as it is tightened against the clamp

member, as shown in Fig. 3, the clamp member exerts a pull on the strap 13. Strap 13 is held against movement by the hooks 22a and accordingly the strap ends with eye members thereon are drawn toward each other, until finally the eyes are centered over the prongs 17, whereupon the rip cord needle 19 is inserted through aperture 20 in the prong to lock the parts together. In actual practice, temporary rip cord needles (not shown) are first inserted to hold the prongs and eyelets together, and these temporary needles are removed just before the rip cord needles 19 are inserted. A groove 29 in the underside of plate 21 provides room for the rip cord 30 (to which needle 15 is secured) as the rip cord must lie between plate 21 and the pack, and plate 21 is tightly pressed against the pack when the pack has been fastened. The device of the invention is removed by merely turning the nut 28 in the opposite direction to disengage the hooks from the eye members, whereupon it may be applied to another pack to repeat the described closing procedure.

Having described my invention, and the preferred manner of using it, what I claim as new and desire to secure by Letters Patent is:

1. A tool for drawing together the straps which bind the folds of a parachute pack, the straps having eye members at their ends, the folds being

fastened by prongs fixed to the pack and passing through eyelets also fixed to the pack, said prongs being passed through the eye members and receiving rip cord needles to lock the parts together 5 until released by pulling the rip cord; said tool comprising a flat plate having a central opening of sufficient size to give access to the prongs; means fixed to one end of the plate to engage an eye member; means at the other end of the 10 plate to engage the eye member on the end of the strap at the opposite side or end of the pack, the last-mentioned means being supported so as to be movable in a direction lengthwise of the plate; a lead screw fixed to said other end of the 15 plate and a nut threaded on the screw and engageable with the last-mentioned means to move the same lengthwise of the plate to tighten said straps.

2. The invention according to claim 1, wherein 20 the last-mentioned means is freely slideable on the lead screw, and the nut is manually rotatable on the lead screw.

3. The invention according to claim 1, wherein 25 the plate also has a longitudinal groove on its underside at one end, said groove permitting a rip cord needle to be inserted through a prong from one end of the plate, and also facilitating withdrawal of the needle.

RALPH T. BLOXON.
